MERCHANDISE DISPLAY STAND

William S. Leath, Birmingham, Ala., assignor to Ebsco Industries, Inc., a corporation of Delaware

Filed Feb. 24, 1969, Ser. No. 15,865

Term of patent 14 years

Int. Cl. D6—01

U.S. Cl. D80—9

Fig. 1

Fig. 2

Fig. 4

Fig. 3

FIG. 1 is a perspective view of a merchandise display stand showing my new design;

FIG. 2 is a front elevational view thereof;

FIG. 3 is a side elevational view thereof, the other side thereof being identical to the side shown; and

FIG. 4 is a top plan view thereof.

I claim:

The ornamental design for a merchandise display stand, as shown and described.
